UNITED STATES PATENT OFFICE.

FRANK E. WILSON, OF CLEVELAND, OHIO, ASSIGNOR TO THE WILSON FASTENER COMPANY, OF CLEVELAND, OHIO, A CORPORATION OF OHIO.

GARTER BUCKLE.

Application filed December 7, 1926. Serial No. 153,067.

This invention is concerned with clasps or buckles and has for its general object the provision of a quickly attachable or detachable buckle adaptable for the joining of the 5 ends of elastic bands.

More specifically, the invention is directed to the provision of a double clamping buckle which, while being neat in appearance, incorporates structural features affording a 10 ready insertion for the cut portions of thick or shirred elastic bands beneath the buckle clasps.

A further object of this invention is the provision of a double clasp buckle for elastic 15 bands which will afford sufficient leverage on the clamping members but which may be arranged in a compact manner convenient and comfortable to the wearer.

Other objects of the invention will become 20 apparent in the following description referring to the accompanying drawings illustrating a preferred embodiment thereof. The essential characteristics are summarized in the claims.

25 Fig. 1 of the drawings shows the adaptation of the buckle to the joining of the ends of stylish elastic bands; Fig. 2 is a front view of the buckle detached from the band; Fig. 3 is a perspective view showing the back face 30 of the buckle; Fig. 4 is a sectional end view of the buckle with the clamping members in a closed or clamping position; the plane of the section being indicated by the line 4—4 on Fig. 2; Fig. 5 is a similar view to Fig. 4 35 with the clamping members swung to open position, thus conditioning the buckle for the reception of the band ends; Fig. 6 is a rear view of the buckle with the clamping members swung to an extreme outward position; Fig. 7 is a perspective view of the under side of one of the clamping members; Fig. 8 is a cross-sectional view taken substantially along the line 8—8 of Fig. 2; and Fig. 9 is a diagrammatic view illustrating the action 40 of the clamping lever, being an exaggerated cross-section through the front and lever.

50 This invention contemplates a double clamping buckle structure which may be applied to the free ends of sleeve or garter bands in a very simple manner, and particularly, bands of the prevailing shirred style wherein the elastic is completely covered by outer layers of tucked or gathered material.

Such bands are considerably thicker and 55 more irregular than the usual flat elastic band heretofore used, and to obtain a buckle which will permit a quick insertion of the jagged thick ends of such a band, and effectively hold them and at the same time shall be comfortable and neat in appearance is a problem 60 which this invention is intended to solve.

The buckle comprises a body 10 and two 65 peculiarly constructed clamping members 20 and 21 hinged thereto. The body of the 70 buckle is outwardly bowed and the clamping members have their jaw surfaces inwardly bowed so that when the clamping members are swung to an open position, a maximum 75 opening is presented to the buckle structure at each side thereof for the reception of the band ends. This maximum opening is shown clearly in Fig. 5, wherein the front or body member 10 of the buckle is formed in forwardly bowed fashion and the jaw surfaces of the clamping members 20 and 21 stand bowed in an opposite direction.

The clamping members, as shown in Fig. 7, may each comprise a stamping having a 80 handle portion as 22 and jaw portion 23 provided with a serrated edge 24 and pivot lugs 25 at its ends.

The body 10 may have the front thereof 85 plain or it may be scrolled or ornamented in any suitable manner, and it may be provided at the top and bottom with flanges 12 which have openings at the ends thereof to receive pivot lugs 25 formed on the clamping members 20 and 21.

The serrated outline or edge 24 of each 90 clamping member is convex and of a curvature so related to the outward bowing of the body that when the clamp is swung into closed position as shown in Figs. 2, 3 and 4, the teeth thereof are closely adjacent and practically 95 contacting with body surfaces adjacent the edge as illustrated particularly in Fig. 4. The teeth 24 are bent from the general concave surface 23 so that these teeth are substantially normal to the front 10 when the buckle 100 is closed.

It will be noted that as shown, the edge 11 of the body is straight and though the surface of the jaw is concaved and the edge convex, this edge when the jaw is closed lies in a 105 plane parallel with the edge of the body, as illustrated in Fig. 2. This peculiar relation of the concave surface of the jaw coacting

with the opposite concavity of the body allows the large space for inversion of material; at the same time the convex termination of the edge causes binding coaction on the body when the jaw is closed. The relationship of the teeth 24 to the body edges 11 causes the greatest impingement of the teeth into the fabric just before the clamping member comes to closed position, thus throwing an extra stress on the device in opening and insuring a binding action of the teeth upon the band when the buckle is closed.

Explaining the action more fully, the clamping jaw is so formed that, in closing, the teeth move slightly past the dead center so that there is no tendency of the buckle to spring open, the tendency being rather to spring tightly shut. The action is more clearly illustrated in the exaggerated view Fig. 9. In this view, which shows the jaw in closed position, C indicates the center about which the clamping jaw swings; the broken line F indicates the inner surface of the front when the buckle is open, and the broken line J indicates the position of the jaw just as the teeth have come into engagement with the front in the closing operation, such an engagement being at the point designated E in the diagram. Now after such engagement takes place, the jaw swings about the center C with a radius C—E and thus springs the front away from the jaw. At the point designated D this spring action has reached the maximum and then the teeth move slightly beyond the line C—D into the position shown at 24, so that the resilience of the front 10 tends to hold the clamping lever against opening movement. It will be understood of course that the amount of displacement of the front is very much exaggerated in Fig. 9 for clearness of illustration.

The arms or lever portions 22 of the clamping members, which extend transversely from one end of the jaw portion, while of sufficient length to enable the jaws to be readily opened, preferably each terminate short of the opposite member. This enables the user to insert the thumb nail beneath the end of the arm and readily force it open. This accessibility may be increased without interfering with the effective smoothness of the back of the buckle, by slightly depressing each clamping member opposite the end of the other as illustrated at 26 in Fig. 3.

Each end flange of the body is preferably indented adjacent the mid region of its extreme edge as shown at 14 to provide an abutment which will be engaged by the lever arm of the clamping member when closed and will thus limit the inward movement and maintain the entire back substantially in a plane, as illustrated in Fig. 3.

From the foregoing description of the invention it will be seen that a buckle structure such as herein set forth may have the exposed

contour thereof of an artistic shape and that such shape is advantageous in that a maximum clearance may be presented between the body of the buckle and the jaws of the clamping members. It will also be apparent that the clamping members may be of a maximum over-all dimension to afford a ready manipulation thereof in both the closing and opening of the buckle. These clamping members may be constructed in such manner as to present a substantially flat back to the buckle with all metallic edges of the buckle subdued to prevent irritation to the wearer. The relationship of the clamping contour to the body contour is such that the elastic band when once clamped by the clamping members, cannot cause an opening movement of the clamping members. For cheapness of manufacture, the two clamping members are identical and may thus be produced by the same dies.

I claim:

1. A buckle comprising a body which is concave on its inner surface and a clamping jaw pivoted to the body and having an edge which is convex and may thus coact with the body when the buckle is closed, said convex edge being carried by a portion of the jaw, the surface of which is concaved toward the body when the buckle is open, whereby a lenticular space is available between the jaw surface and the body surface.

2. A buckle substantially of the character described, wherein the body member is formed with a convex outer surface bounded by straight edges and clamping members pivoted thereto having concave jaw surfaces, on the side adjacent the body when the buckle is open and such surfaces having edges convexed in the same direction as the body, which edges, when the jaws are closed lie in a plane parallel with the edge of the body.

3. A buckle of the character described, the combination of a sheet metal body portion having flanged ends, a pair of clamping members pivotally mounted in said ends, each clamping member comprising a jaw portion which has a concave surface adapted to stand away from the body when the buckle is open, there being teeth at the inner edge of such concaved surface which coacts with the body when the buckle is closed, each jaw portion having a lever arm adjacent one end extending towards the opposite clamping member and a portion of the end flanges of the body being bent inwardly to provide abutments adapted to be engaged by the lever arms.

4. In a buckle, a buckle body having its surface concavely formed and a clamping member pivotally connected thereto which when in an open position is formed with a jaw surface to be concave in an opposite direction relative to the body concavity.

5. In a buckle, the combination of a pair of clamping members, said clamping members having jaws, the outer surface of which

is concavely formed and a body member to which the clamping members are pivotally attached, said body member having its inner surface concavely formed in an opposite direction relative to the clamping member when the latter are swung to an open or unclamping position.

6. As a new article of manufacture, a double buckle comprising a body portion and two clamping jaws hinged thereto, each jaw having a comparatively wide portion extending toward the body when the buckle is closed and terminating in a comparatively narrow gripping edge, the surface of the said portion being bowed in an arc of which the pivotal axis is substantially a chord, so that said surface will stand away from the body when the jaws are open.

7. A buckle for connecting the ends of garter bands or the like comprising a body portion and two clamping jaws pivoted thereto at opposite ends, each jaw having an edge

adapted substantially to engage the surface of the body when the buckle is closed, such edge forming the terminus of a jaw surface, 25 of material width, which lies in an arc from one pivot to the other and is concaved or hollowed toward the body when the buckle is open.

8. A double buckle having a body and two clamping members, said body being concave on the face adjacent the clamping members, said clamping member having a jaw and a lever arm, the clamping members being duplicates and each lever arm projecting from near 35 one end of one member toward the other member, and the jaw comprising a surface which is concave toward the body when the buckle is open, said surface terminating in a convex edge adapted to coact with the body when the buckle is closed.

In testimony whereof, I hereunto affix my signature.

FRANK E. WILSON.
